FORMING MACHINE

Guy O. Conner, Cleveland Heights, Ohio, assignor,
by mesne assignments, to Danly Machine Spe-
cialties, Inc., a corporation of Illinois

Application August 17, 1945, Serial No. 611,081

23 Claims. (Cl. 74—571)

1

This invention relates to forming machines and more particularly to forming machines operated by eccentric means mounted on one or more shafts, the eccentric means carrying one or more heads or other working parts which during operation of the machine partake of cyclic movement. The invention has to do particularly with adjustment of the relative angular positions of the eccentric means and the shaft or shafts on which the eccentric means are to be mounted. Such adjustment is accomplished by holding the eccentric means or certain thereof against rotation while turning the shaft or shafts. The invention further relates to other novel features and combinations of elements employed in a forming machine in connection with the adjusting mechanism.

The invention is adaptable for use in forming machines such, for example, as that disclosed in my copending application Serial No. 497,792, now Patent #2,496,808. Such a forming machine may comprise upper and lower heads each partaking of orbital movement and which cooperate to perform operations on moving work. For example, the heads may carry dies which stamp or otherwise form work passing through the machine. Each head may, for example, be mounted on two parallel shafts rotating in the same direction. Thus the machine may comprise four parallel shafts, two in a horizontal plane and the other two in a second horizontal plane below the first two, each upper shaft being in the same vertical plane as one of the lower shafts. The two upper shafts rotate in one direction and the lower shafts rotate in the opposite direction. The four shafts carry eccentrics upon which the heads are mounted. Thus when the shafts are operating the respective heads move in orbits so that the dies or other working means carried thereby periodically cooperate to act on the work, at the same time moving laterally.

It is desirable in forming machines of the type above referred to to counterbalance the heads by counterweights. For example, there may be a counterweight for counterbalancing the upper head and a counterweight for counterbalancing the lower head such as disclosed in my copending application Serial No. 611,080. The counterweight for counterbalancing the upper head may be mounted on the same two shafts on which the upper head is mounted and the counterweight for counterbalancing the lower head may be mounted on the same two shafts on which the lower head is mounted. Each counterweight is mounted on eccentrics carried by the shaft. The eccentrics are so constructed and arranged that each counterweight exerts its force on the shafts carrying it at any given instant in a direction substantially opposite the direction in which the head carried by those shafts is exerting its force

2

at the same instant. To bring about this result the high points, or points farthest removed from the shaft axes, of the eccentrics carrying the head should be disposed substantially in the opposite direction from the shaft axes relatively to the high points of the eccentrics carrying the corresponding counterweight.

To render a forming machine of the type referred to adaptable for various operations and for operating on work of various thicknesses and characteristics it is desirable that the eccentricity or throw of the eccentrics carrying the heads and counterweights be adjustable. In my said copending application Serial No. 611,080 there is disclosed mechanism for adjusting the eccentrics so that when the throw of the eccentrics carrying the heads is adjusted the throw of the eccentrics carrying the counterweights will likewise be adjusted and the respective eccentrics will automatically maintain proper angular relationship about the shafts upon which they are mounted. Each head and each counterweight is mounted on an eccentric or eccentrics carried by each shaft supporting it with an eccentric sleeve disposed about each eccentric so that each resultant eccentric device acting on the head or counterweight as the case may be consists of the eccentric on the shaft and the eccentric sleeve thereabout, in other words, an eccentric and eccentric sleeve combination or resultant eccentric made up of an eccentric with an eccentric sleeve thereabout. The throw of the resultant eccentric is altered by relatively turning the eccentric sleeve and the shaft upon which it is mounted and which carries in non-rotative relationship the eccentric lying within the eccentric sleeve. In my said copending application Serial No. 611,080 I show means for insuring turning of the eccentric sleeves carrying the heads and the eccentric sleeves carrying the counterweights in controlled relationship so that the high points of the resultant eccentrics carrying the heads are disposed approximately 180° about the shafts from the high points of the resultant eccentrics carrying the counterweights.

Since the eccentric sleeves are mounted about the shafts and the heads and counterweights are mounted about the eccentric sleeves, the eccentric sleeves are difficultly accessible for angular adjustment on the shafts. I have therefore provided means facilitating relative angular adjustment between the eccentric sleeves and shafts and also means whereby the eccentric sleeves and shafts may be fixedly positioned relatively to each other in adjusted angular positions, which means may be rendered temporarily inoperative to permit of angular adjustment between the sleeves and the shafts.

I provide, in a forming machine, a shaft, eccentric means on the shaft, the eccentric means

and shaft being relatively turnable to adjusted positions but fixedly positionable relatively to each other in said adjusted positions, means mounted on the eccentric means to be operated thereby upon rotation of the shaft and means for holding the eccentric means against rotation while turning the shaft to adjust the relative angular positions of the eccentric means and shaft. I preferably provide means engaging at least certain of the eccentric means and a head mounted on such eccentric means for holding the eccentric means temporarily against turning movement relatively to the head while the shaft is turned. Such means are preferably connected with the head and adapted to be temporarily disposed so as to engage the eccentric means to hold the same against turning movement relatively to the head. Desirably screw means may be employed which are connected with the head and which are adapted to be turned up against the eccentric means. The eccentric means may have a radial flange and the screw means may when turned up engage the flange of the eccentric means to hold the eccentric means temporarily against turning movement relatively to the head while the shaft is turned.

I further provide, in a forming machine, a shaft, eccentric means on the shaft, the eccentric means and shaft being relatively turnable to adjusted positions, means on the eccentric means and shaft engageable to fixedly position the eccentric means and shaft relatively to each other in said adjusted positions and disengageable to permit relative turning of the eccentric means and shaft, means mounted on the eccentric means to be operated thereby upon rotation of the shaft and means for holding the eccentric means against rotation while turning the shaft to adjust the relative angular positions of the eccentric means and shaft. The means on the eccentric means and shaft to fixedly position the eccentric means and shaft relatively to each other in adjusted positions are preferably engageable upon relative axial movement between the eccentric means and shaft in one direction and disengageable upon relative axial movement between the eccentric means and shaft in the opposite direction. The shaft preferably has means projecting generally parallel to its axis but offset therefrom adapted to interengage with portions of the eccentric means when the eccentric means is moved axially of the shaft and means are preferably provided for maintaining the eccentric means in interengagement with said projecting means on the shaft, said last mentioned means being operable to permit disengagement of the eccentric means and said projecting means on the shaft so that the eccentric means and shaft may turn relatively to each other. I preferably provide teeth on the eccentric means and shaft engageable upon relative axial movement between the eccentric means and shaft in one direction and disengageable upon relative axial movement between the eccentric means and shaft in the opposite direction.

I still further provide, in a forming machine, a shaft, a plurality of eccentric means on the shaft, the eccentric means and shaft being relatively turnable to adjusted positions but fixedly positionable relatively to each other in said adjusted positions, connections between the eccentric means effecting predetermined relative turning between one of the eccentric means and the shaft upon predetermined relative turning between another of the eccentric means and the shaft,

means mounted on the respective eccentric means to be operated thereby upon rotation of the shaft and means for holding one of the eccentric means against rotation while turning the shaft to adjust the relative angular positions of said eccentric means and the shaft.

I further provide, in a forming machine, a shaft, eccentric means on the shaft, the eccentric means and shaft being relatively turnable to adjusted positions but fixedly positionable relatively to each other in said adjusted positions, means mounted on the eccentric means to be operated thereby upon rotation of the shaft, means for holding the eccentric means against rotation while turning the shaft to adjust the relative angular positions of the eccentric means and shaft and means including index means applicable to an end of the shaft for turning the shaft through a predetermined angle. The means for turning the shaft may comprise a sleeve applicable to an end of the shaft in non-rotative relation to the shaft, the sleeve having index means to facilitate turning of the shaft through a predetermined angle.

Other details, objects and advantages of the invention will become apparent as the following description of a present preferred embodiment thereof proceeds.

In the accompanying drawings I have shown a present preferred embodiment of the invention in which

Figure 1 is a vertical cross-sectional view through a forming machine, the section being taken transversely of the direction of feed of work through the machine;

Figure 2 is a vertical cross-sectional view taken on the line II—II of Figure 1;

Figure 3 is an enlarged fragmentary vertical cross-sectional view of a portion of the structure shown in Figure 1 but with the retaining nut and sleeve removed and an indexed sleeve applied to the end of the shaft for turning it through a predetermined angle to relatively adjust the eccentric sleeves and the shaft, certain of the eccentric sleeves being shown as maintained against rotation relatively to the head;

Figure 4 is an end view of the structure shown in Figure 3 as viewed from the right hand end of Figure 3;

Figure 5 is a fragmentary elevational view showing the indexed sleeve applied to the shaft, and

Figure 6 is a fragmentary elevational view to enlarged scale of the indexed sleeve for turning the shaft.

Referring now more particularly to the drawings, there is shown a forming machine having an upper forming head 2, a lower forming head 3, an upper counterweight 4 and a lower counterweight 5. The upper head 2 and the upper counterweight 4 are mounted on two parallel upper shafts 6 and 7. The lower head 3 and the lower counterweight 5 are mounted on two parallel lower shafts 8 and 9. All four of the shafts 6, 7, 8 and 9 are parallel to one another, the shafts 6 and 7 lying in a horizontal plane and the shafts 8 and 9 lying in a lower horizontal plane. The shafts 6 and 8 lie in the same vertical plane and the shafts 7 and 9 lie in the same vertical plane.

The shafts 6 and 7 are rotated in one direction and the shafts 8 and 9 are rotated in the opposite direction. Referring to Figure 2, if, for example, the shafts 6 and 7 rotate clockwise the shafts 8 and 9 rotate counterclockwise. All four shafts are rotated in unison at the same speed

by any suitable driving mechanism, such, for example as the driving mechanism shown in my said copending application Serial No. 497,792. Driving mechanism for the shafts is shown at the left hand side of Figure 1 but since the driving mechanism forms no part of the present invention it will not be described in detail. The outer or right hand ends of the shafts viewing Figure 1 are mounted in outboard bearings 10.

One of the shafts is shown fragmentarily to enlarged scale in Figure 3, although in that figure the outboard bearing 10 has been removed as have the retaining nut and sleeve on the end of the shaft and an indexed sleeve for turning the shaft has been applied. The shaft comprises portions 11 and 12 for journaling the shaft for rotation and, intermediate those portions, eccentric portions 13, 14 and 14a. The portion 11 is concentric with the shaft axis. The portion 12 is eccentric with respect to the shaft axis but is adapted to receive thereover an eccentric sleeve 12a (Figure 1) keyed thereto. When the eccentric sleeve 12a is applied to the shaft portion 12 the outer cylindrical surface of the sleeve 12a is concentric with the shaft axis. Therefore the shaft rotates in bearings cooperating with the portion 11 of the shaft and the sleeve 12a keyed to the shaft.

The eccentric shaft portions 13 and 14a form eccentrics for mounting one of the heads, as, for example, the upper head 2. The head straddles the counterweight which is mounted about the eccentric shaft portion 14. In Figures 1 and 3 the high points of the eccentrics 13 and 14a are disposed upwardly. The eccentric for mounting the counterweight is shown at 15, being keyed to the shaft and its high point extending downwardly or diametrically opposite the high points of the eccentrics 13 and 14a. The eccentric 15 is applied to the shaft at the eccentric portion 14 thereof as shown in Figure 1, being keyed thereto by a key 15a.

The shaft has a radial flange 16 against which lies a member 17 which through projections 18 carried thereby and which respectively enter recesses 19 in the flange 16 is held against turning movement relatively to the shaft. The member 17 has a circumferential series of teeth 20 facing axially toward the right viewing Figures 1 and 3.

An eccentric sleeve 21 having a radial flange 21a is mounted on the eccentric 13 and has teeth 22 normally in mesh with the teeth 20. The sleeve 21 in its normal position is disposed relatively to the eccentric 13 so that the high point of the sleeve is in the same plane containing and in the same direction from the shaft axis as the high point of the eccentric. In its end face the flange 21a has radial projections 23 which are radially aligned with each other and one of which passes through the high point of the eccentric sleeve. An annular member 24 is disposed about the shaft to the right of the sleeve 21 viewing Figures 1 and 3 and has in its left hand face viewing such figures aligned radial slots 25 and in its right hand face other aligned radial slots which extend at right angles to the slots 25. The bore of the annular member 24 is, as shown, much larger than the shaft so that the member 24 is free to move transversely of the shaft as well as angularly. The radial projections 23 enter and are guidingly received by the slots 25 so that the sleeve 21 and the annular member 24 may not rotate relatively to one another but may partake only of relative movement longitudinally of the projections 23, this being permitted because

the bore of the member 24 is larger than the shaft.

Mounted over the eccentric 15 is an eccentric sleeve 31 having aligned radial projections 31a at its left and right hand faces, all of which projections are in the same plane containing the shaft axis which extends at right angles to a plane containing the shaft axis and passing through the high point of the eccentric sleeve 31. In other words the projections 31a on the end faces of the eccentric sleeve 31 lie in a plane perpendicular to the plane of the paper viewing each of Figures 1 and 3.

The projections 31a at the left hand face of the eccentric sleeve 31 are guidingly received by the slots 31b in the right hand face of the annular member 24. Thus the annular member 24 and the sleeve 31 may not relatively rotate but may partake of relative movement longitudinally of the interfitting projections 31a and slots 31b. The sleeve 31 is normally disposed with its high point in the same plane containing and in the same direction from the shaft axis as the high point of the eccentric 15.

Mounted next the sleeve 31 is a member 34 similar to the member 24 and having aligned radial slots 34c in its left hand face which extend at right angles to the plane of the papers viewing each of Figures 1 and 3 and aligned radial slots 36 in its right hand face, the slots 36 extending in the plane of the paper viewing each of Figures 1 and 3 and hence being disposed at right angles to the slots 34c in the left hand face of the member 34. The member 34 like the member 24 has a bore larger than the shaft so that the member 34 may move transversely of the shaft. The projections 31a at the right hand face of the eccentric sleeve 31 enter and are guidingly received by the slots 34c in the left hand face of the annular member 34.

Mounted on the eccentric 14a is an eccentric sleeve 39 having a flange 39a having aligned radial portions 39b, the eccentric sleeve 39 being similar to the eccentric sleeve 21. The projections 39b extend through the high point of the sleeve 39. The high point of the sleeve is normally in the same plane containing and in the same direction from the shaft axis as the high point of the eccentric 14a. The projections 39b enter and are guidingly received by the slots 36 of the annular member 34. Thus the member 34 and the sleeve 39 may not relatively rotate but may move relatively to each other longitudinally of the projections 39b. In its right hand face the eccentric sleeve 39 has teeth 40 adapted to mesh with teeth 40a on the eccentric sleeve 12a. A retaining nut 40b is threaded onto the shaft and bears against the right hand end of the sleeve 12a to hold the members assembled.

When one of the eccentric sleeves 21 and 39 and the shaft are relatively turned the mechanism just described results in correspondingly relatively turning the other of such sleeves and the shaft and also in relatively turning the eccentric sleeve 31 and the shaft to maintain parallel planes through the shaft axis and through the high points of the eccentric sleeves 21, 39 and 31. The result of this is to maintain the high points of the resultant eccentrics or eccentric and eccentric sleeve combinations for the head and counterweight respectively directly opposite each other relative to the shaft axis. This insures that the head and counterweight will always act on the shaft in opposite directions. When the sleeve 12a is in place as shown in Figure 1 and the nut 40b is turned up against the end of that sleeve

all of the eccentric sleeves 21, 31 and 39 are fixedly positioned relatively to each other and relatively to the shaft just as though the sleeves were integral parts of the shaft. This is because the member 17 is non-rotatably mounted on the shaft, the teeth 20 on that member are in mesh with the teeth 22 on the sleeve 21, the sleeves 21 and 31 are held in fixed relation with respect to each other by the annular member 24, the sleeves 31 and 39 are held in fixed relation with respect to each other by the annular member 34 and the teeth 40 on the sleeve 39 are in mesh with the teeth 40a on the sleeve 12a, which sleeve 12a is keyed to the shaft.

When it is desired to relatively angularly adjust the shafts and the sleeves carried thereby the outboard bearings 10 are removed, the nuts 40b are removed from the ends of the shafts and the sleeves 12a are likewise removed. This leaves the eccentric sleeves 21, 31 and 39 loose upon their respective eccentrics 13, 14 and 14a and free to partake of sufficient movement axially of the shafts to disengage the teeth 20 and 22. Of course when the sleeve 12a is removed the teeth 40 and 40a are disengaged. With all the teeth thus disengaged the sleeves 21, 31 and 39 are free to turn relatively to the shafts.

As above stated I provide for relatively angularly adjusting the eccentric sleeves and shafts by holding certain of the eccentric sleeves against rotation and turning the shafts therein. I hold the eccentric sleeves 21 and 39 against movement relatively to the head 2 by means of screws 41 which are mounted in threaded bores in the head and are adapted to be turned so as to thread inwardly or toward the shaft until their noses engage the flanges 21a and 39a of the sleeves 21 and 39, respectively. The screws 41 have flat heads so that they create sufficient frictional resistance when turned up tightly against the sleeve flanges to hold the sleeves against turning. When the screws have been turned up to engage the sleeve flanges and the outboard bearing 10, nut 40b and sleeve 12a have been removed a special sleeve 42 is fitted over the end of the shaft. The sleeve 42 is keyed to the shaft so as to be non-rotatable with respect thereto. It is externally knurled so as to be adapted to be gripped and turned by a wrench. The sleeve 42 has index means 43 thereon to facilitate turning of the shaft through a predetermined angle. The index means on the sleeve 42 may cooperate with an index mark 44 on the sleeve 39.

When the shaft is turned by the use of the sleeve 42 it will rotate relatively to the sleeves 21 and 39 which by the screws are fixedly held relatively to the head 2 so that they cannot turn. The connections above described between the eccentric sleeves 21, 31 and 39 insure predetermined relative turning between the eccentric sleeve 31 and the shaft upon predetermined relative turning between the eccentric sleeves 21 and 39 and the shaft. As explained above, such connections insure that planes through the shaft axis and through the high points of the eccentric sleeves 21, 31 and 39 are maintained parallel which in turn results in the force of the counterweight always being exerted at a point diametrically opposite the point on the shaft at which the force of the head is exerted.

When the shaft has been turned to the desired extent the sleeve 42 is removed, the screws 41 are threaded back clear of the sleeve flanges and the sleeve 12a, the nut 40b and the outboard bearing 10 are replaced. The sleeves are then held in

fixed position relatively to each other and to the shaft and the machine is again ready for operation.

Since the shafts are all geared together for operation in unison it is only necessary that one of the four shafts be turned in the manner above described to effect adjustment of all. Turning of one shaft results through the connecting gearing in turning of all four shafts. However it is necessary to turn up the screws 41 to hold all eight of the eccentric sleeves for mounting the heads against turning and to remove or at least loosen all of the holding nuts and sleeves. The holding sleeves corresponding to the sleeve 12a must be capable of movement toward the ends of the shafts far enough to permit complete disengagement of both sets of teeth corresponding to the teeth 20 and 22 and the teeth 40 and 40a. After the adjustment has been effected all of the screws 41 should be turned back to clear the flanges of the eccentric sleeves and the holding sleeves and nuts should be applied to all four shafts. The outboard bearings should of course also be applied to all four shafts before the machine is again put in operation.

While I have shown and described a present preferred embodiment of the invention it is to be distinctly understood that the invention is not limited thereto but may be otherwise variously embodied within the scope of the following claims.

I claim:

1. In a forming machine, a shaft, eccentric means on the shaft, the eccentric means and shaft being relatively turnable to adjusted positions but fixedly positionable relatively to each other in said adjusted positions, a head mounted on the eccentric means to be operated thereby upon rotation of the shaft and means engaging the eccentric means and the head for holding the eccentric means temporarily against turning movement relatively to the head while the shaft is turned to adjust the relative angular positions of the eccentric means and shaft.

2. In a forming machine, a shaft, eccentric means on the shaft, the eccentric means and shaft being relatively turnable to adjusted positions but fixedly positionable relatively to each other in said adjusted positions, a head mounted on the eccentric means to be operated thereby upon rotation of the shaft and means connected with the head adapted to be temporarily disposed so as to engage the eccentric means to hold the same against turning movement relatively to the head while the shaft is turned to adjust the relative angular positions of the eccentric means and shaft.

3. In a forming machine, a shaft, eccentric means on the shaft, the eccentric means and shaft being relatively turnable to adjusted positions but fixedly positionable relatively to each other in said adjusted positions, a head mounted on the eccentric means to be operated thereby upon rotation of the shaft and screw means connected with the head adapted to be turned up against the eccentric means to hold the same temporarily against turning movement relatively to the head while the shaft is turned to adjust the relative angular positions of the eccentric means and shaft.

4. In a forming machine, a shaft, eccentric means on the shaft, the eccentric means having a radial flange, the eccentric means and shaft being relatively turnable to adjusted positions but fixedly positionable relatively to each other

in said adjusted positions, a head mounted on the eccentric means to be operated thereby upon rotation of the shaft and screw means connected with the head adapted to be turned up against the flange of the eccentric means to hold the eccentric means temporarily against turning movement relatively to the head while the shaft is turned to adjust the relative angular positions of the eccentric means and shaft.

5. In a forming machine, a shaft, eccentric means on the shaft, the eccentric means and shaft being relatively turnable to adjusted positions, means on the eccentric means and shaft engageable upon relative axial movement between the eccentric means and shaft in one direction to fixedly position the eccentric means and shaft relatively to each other in said adjusted positions and disengageable upon relative axial movement between the eccentric means and shaft in the opposite direction to permit relative turning of the eccentric means and shaft, means mounted on the eccentric means to be operated thereby upon rotation of the shaft and screw means threaded into said last mentioned means adapted to be turned up to engage the eccentric means for holding the eccentric means against rotation while turning the shaft to adjust the relative angular positions of the eccentric means and shaft.

6. In a forming machine, a shaft, eccentric means on the shaft, the eccentric means and shaft being relatively turnable to adjusted positions, the shaft having means projecting generally parallel to its axis but offset therefrom adapted to interengage with portions of the eccentric means when the eccentric means is moved axially of the shaft in one direction to fixedly position the eccentric means and shaft relatively to each other in said adjusted positions, means for maintaining the eccentric means in interengagement with said projecting means on the shaft, said last mentioned means being operable to permit disengagement of the eccentric means and said projecting means on the shaft so that the eccentric means and shaft may turn relatively to each other, means mounted on the eccentric means to be operated thereby upon rotation of the shaft and screw means adapted to be turned up to engage the eccentric means for holding the eccentric means against rotation while turning the shaft to adjust the relative angular positions of the eccentric means and shaft.

7. In a forming machine, a shaft, eccentric means on the shaft, the eccentric means and shaft being relatively turnable to adjusted positions, teeth on the eccentric means and shaft engageable upon relative axial movement between the eccentric means and shaft in one direction to fixedly position the eccentric means and shaft relatively to each other in said adjusted positions and disengageable upon relative axial movement between the eccentric means and shaft in the opposite direction to permit relative turning of the eccentric means and shaft, means mounted on the eccentric means to be operated thereby upon rotation of the shaft and clamping means adapted to engage the eccentric means for holding the eccentric means against rotation while turning the shaft to adjust the relative angular positions of the eccentric means and shaft.

8. In a forming machine, a shaft, a plurality of eccentric means on the shaft, the eccentric means and shaft being relatively turnable to adjusted positions but fixedly positionable relatively

to each other in said adjusted positions, connections between the eccentric means effecting predetermined relative turning between one of the eccentric means and the shaft upon predetermined relative turning between another of the eccentric means and the shaft, means mounted on the respective eccentric means to be operated thereby upon rotation of the shaft and means for holding one of the eccentric means against rotation while turning the shaft to adjust the relative angular positions of the eccentric means and the shaft.

9. In a forming machine, a shaft, eccentric means on the shaft, the eccentric means and shaft being relatively turnable to adjusted positions, the shaft having means adapted to interengage with portions of the eccentric means when the eccentric means is moved axially of the shaft in one direction to fixedly position the eccentric means and shaft relatively to each other in said adjusted positions, means for maintaining the eccentric means in interengagement with said means on the shaft, said last mentioned means being operable to permit disengagement of the eccentric means and said means on the shaft so that the eccentric means and shaft may turn relatively to each other, means mounted on the eccentric means to be operated thereby upon rotation of the shaft and means adapted to be rendered operative and inoperative and when operative bearing against the eccentric means for holding the eccentric means against rotation while turning the shaft to adjust the relative angular positions of the eccentric means and shaft.

10. In a forming machine, a shaft, eccentric means on the shaft, the eccentric means having teeth, the eccentric means and shaft being relatively turnable to adjusted positions, the shaft having teeth adapted to interengage with the teeth of the eccentric means when the eccentric means is moved axially of the shaft in one direction to fixedly position the eccentric means and shaft relatively to each other in said adjusted positions, means for maintaining the eccentric means in position with its teeth in interengagement with the teeth on the shaft, said last mentioned means being operable to permit disengagement of the teeth on the eccentric means and the teeth on the shaft so that the eccentric means and the shaft may turn relatively to each other, means mounted on the eccentric means to be operated thereby upon rotation of the shaft and releasable means carried by said last mentioned means adapted to be rendered operative for holding the eccentric means against rotation while turning the shaft to adjust the relative angular positions of the eccentric means and shaft.

11. In a forming machine, a shaft, a plurality of eccentric means on the shaft, the eccentric means and shaft being relatively turnable to adjusted positions, connections between the eccentric means effecting predetermined relative turning between one of the eccentric means and the shaft upon predetermined relative turning between another of the eccentric means and the shaft, means on one of the eccentric means and the shaft engageable upon relative axial movement between the eccentric means and the shaft in one direction to fixedly position the eccentric means and shaft relatively to each other in said adjusted positions and disengageable upon relative axial movement between the eccentric means and the shaft in the opposite direction to permit

11

relative turning of the eccentric means and shaft, means mounted on the respective eccentric means to be operated thereby upon rotation of the shaft and means for holding one of the eccentric means against rotation while turning the shaft to adjust the relative angular positions of said eccentric means and the shaft.

12. In a forming machine, a shaft, a plurality of eccentric means on the shaft, the eccentric means and shaft being relatively turnable to adjusted positions, connections between the eccentric means effecting predetermined relative turning between one of the eccentric means and the shaft upon predetermined relative turning between another of the eccentric means and the shaft, the eccentric means having teeth, the shaft having teeth adapted to interengage with the teeth of the eccentric means when the eccentric means is moved axially of the shaft in one direction to fixedly position the eccentric means and shaft relatively to each other in said adjusted positions, means for maintaining the eccentric means in position with its teeth in interengagement with the teeth on the shaft, said last mentioned means being operable to permit disengagement of the teeth on the eccentric means and the teeth on the shaft so that the eccentric means and the shaft may turn relatively to each other, means mounted on the respective eccentric means to be operated thereby upon rotation of the shaft and means for holding one of the eccentric means against rotation while turning the shaft to adjust the relative angular positions of said eccentric means and the shaft.

13. In a forming machine, a shaft, a plurality of eccentric means on the shaft, the eccentric means and shaft being relatively turnable to adjusted positions, connections between the eccentric means effecting predetermined relative turning between one of the eccentric means and the shaft upon predetermined relative turning between another of the eccentric means and the shaft, the eccentric means having two sets of teeth, one facing generally axially of the shaft in each direction, the shaft having teeth adapted to interengage with one of the sets of teeth on the eccentric means when the eccentric means is moved axially of the shaft in one direction to fixedly position the eccentric means and shaft relatively to each other in said adjusted positions, means for maintaining the eccentric means in position with its first mentioned set of teeth in interengagement with the teeth on the shaft, said last mentioned means having teeth interengageable with the other set of teeth on the eccentric means and being operable to permit disengagement of both sets of teeth on the eccentric means with the teeth on the shaft and on said last mentioned means respectively so that the eccentric means and the shaft may turn relatively to each other, means mounted on the respective eccentric means to be operated thereby upon rotation of the shaft and means for holding one of the eccentric means against rotation while turning the shaft to adjust the relative angular positions of said eccentric means and the shaft.

14. In a forming machine, a shaft, eccentric means on the shaft, the eccentric means and shaft being relatively turnable to adjusted positions, the shaft having means adapted to interengage with portions of the eccentric means when the eccentric means is moved axially of the shaft in one direction to fixedly position the eccentric means and shaft relatively to each

12

other in said adjusted positions, a sleeve fitting over the shaft and adapted to abut the eccentric means to maintain the eccentric means in interengagement with said means on the shaft, means for maintaining the sleeve in position, said last mentioned means being adapted to be rendered inoperative to permit retraction of the sleeve and consequent disengagement of the eccentric means and said means on the shaft so that the eccentric means and shaft may turn relatively to each other, means mounted on the eccentric means to be operated thereby upon rotation of the shaft and means for holding the eccentric means against rotation while turning the shaft to adjust the relative angular positions of the eccentric means and shaft.

15. In a forming machine, a shaft, eccentric means on the shaft, the eccentric means and shaft being relatively turnable to adjusted positions, the shaft having means adapted to interengage with portion of the eccentric means when the eccentric means is moved axially of the shaft in one direction to fixedly position the eccentric means and shaft relatively to each other in said adjusted positions, a sleeve fitting over the shaft and adapted to abut the eccentric means to maintain the eccentric means in interengagement with said means on the shaft, means for maintaining the sleeve in position, said last mentioned means being adapted to be rendered inoperative to permit retraction of the sleeve and consequent disengagement of the eccentric means and said means on the shaft so that the eccentric means and shaft may turn relatively to each other, bearing means for the shaft cooperating with the sleeve when in position thereon, the bearing means being retractable to permit retraction of the sleeve, means mounted on the eccentric means to be operated thereby upon rotation of the shaft and means for holding the eccentric means against rotation while turning the shaft to adjust the relative angular positions of the eccentric means and shaft.

16. In a forming machine, a shaft, eccentric means on the shaft, the eccentric means and shaft being relatively turnable to adjusted positions but fixedly positionable relatively to each other in said adjusted positions, means mounted on the eccentric means to be operated thereby upon rotation of the shaft, means for holding the eccentric means against rotation while turning the shaft to adjust the relative angular positions of the eccentric means and shaft and means including index means applicable to an end of the shaft for turning the shaft through a predetermined angle.

17. In a forming machine, a shaft, eccentric means on the shaft, the eccentric means and shaft being relatively turnable to adjusted positions but fixedly positionable relatively to each other in said adjusted positions, means mounted on the eccentric means to be operated thereby upon rotation of the shaft, means for holding the eccentric means against rotation while turning the shaft to adjust the relative angular positions of the eccentric means and shaft and a sleeve applicable to an end of the shaft in non-rotative relation to the shaft for turning the shaft, the sleeve having index means to facilitate turning of the shaft through a predetermined angle.

18. In a forming machine, a shaft, eccentric means on the shaft, the eccentric means and shaft being relatively turnable to adjusted positions, means mounted on the eccentric means

to be operated thereby upon rotation of the shaft, means for holding the eccentric means against rotation while turning the shaft to adjust the relative angular positions of the eccentric means and shaft, means including a sleeve applicable over an end of the shaft and means for maintaining the sleeve in position abutting the eccentric means for fixedly positioning the eccentric means and shaft relatively to each other, and a second sleeve applicable to said end of the shaft in non-rotative relation to the shaft for turning the shaft, said second sleeve having index means to facilitate turning of the shaft through a predetermined angle.

19. In a forming machine, a shaft, eccentric means on the shaft, the eccentric means and shaft being relatively turnable to adjusted positions, means mounted on the eccentric means to be operated thereby upon rotation of the shaft, means for holding the eccentric means against rotation while turning the shaft to adjust the relative angular positions of the eccentric means and shaft, means including a sleeve applicable over an end of the shaft and means for maintaining the sleeve in position abutting the eccentric means for fixedly positioning the eccentric means and shaft relatively to each other, bearing means for the shaft cooperating with said sleeve when in said position thereon, the bearing means being retractable to permit retraction or removal of said sleeve, and a second sleeve applicable to said end of the shaft in non-rotative relation to the shaft for turning the shaft when said first mentioned sleeve and said bearing means have been removed, said second sleeve having index means to facilitate turning of the shaft through a predetermined angle.

20. In a forming machine, a shaft, eccentric means on the shaft, the eccentric means and shaft being relatively turnable to adjusted positions, the shaft having means adapted to interengage with portions of the eccentric means when the eccentric means is moved axially of the shaft in one direction to fixedly position the eccentric means and shaft relatively to each other in said adjusted positions, a sleeve applicable over an end of the shaft and adapted to abut the eccentric means to maintain the eccentric means in interengagement with said means on the shaft, means for maintaining the sleeve in position, said last mentioned means being adapted to be rendered inoperative to permit retraction of the sleeve and consequent disengagement of the eccentric means and said means on the shaft so that the eccentric means and shaft may turn relatively to each other, bearing means for the shaft cooperating with said sleeve when in operative position thereon, the bearing means being retractable to permit retraction or removal of said sleeve, a second sleeve applicable to said end of the shaft in non-rotative relation to the shaft for turning the shaft when said first mentioned sleeve and said bearing means have been removed, said second sleeve having index means to facilitate turning of the shaft through a predetermined angle, means mounted on the eccentric means to be operated thereby upon rotation of the shaft and means for holding the eccentric means against rotation while turning the shaft to adjust the relative angular positions of the eccentric means and shaft.

21. In a forming machine, a shaft, a plurality of eccentric means on the shaft, the eccentric means and shaft being relatively turnable to

adjusted positions, connections between the eccentric means effecting predetermined relative turning between one of the eccentric means and the shaft upon predetermined relative turning between another of the eccentric means and the shaft, the shaft having means adapted to interengage with portions of the eccentric means when the eccentric means is moved axially of the shaft in one direction to fixedly position the eccentric means and shaft relatively to each other in said adjusted positions, the eccentric means being movable axially of the shaft in the opposite direction to disengage the eccentric means and said means on the shaft so that the eccentric means and shaft may turn relatively to each other, a sleeve applicable to an end of the shaft in non-rotative relation to the shaft for turning the shaft, said sleeve having index means to facilitate turning of the shaft through a predetermined angle, means mounted on the respective eccentric means to be operated thereby upon rotation of the shaft and means for holding one of the eccentric means against rotation while turning the shaft to adjust the relative angular positions of the eccentric means and the shaft.

22. In a forming machine, a shaft, eccentric means on the shaft, the eccentric means and shaft being relatively turnable to adjusted positions but fixedly positionable relatively to each other in said adjusted positions, means mounted on the eccentric means to be operated thereby upon rotation of the shaft and releasable means carried by said last mentioned means opposite a portion of the eccentric means advanceable to engage said portion of the eccentric means for holding the eccentric means against rotation while turning the shaft to adjust the relative angular positions of the eccentric means and shaft.

23. In a forming machine, a shaft, eccentric means on the shaft, the eccentric means and shaft being relatively turnable to adjusted positions, means on the eccentric means and shaft engageable to fixedly position the eccentric means and shaft relatively to each other in said adjusted positions and disengageable to permit relative turning of the eccentric means and shaft, means mounted on the eccentric means to be operated thereby upon rotation of the shaft and releasable means carried by said last mentioned means opposite a portion of the eccentric means advanceable to engage said portion of the eccentric means for holding the eccentric means against rotation while turning the shaft to adjust the relative angular positions of the eccentric means and shaft.

GUY O. CONNER.
